UNITED STATES PATENT OFFICE

OTTO DE LORENZI, OF MAPLEWOOD, NEW JERSEY, ASSIGNOR TO INTERNATIONAL COMBUSTION ENGINEERING CORPORATION, OF NEW YORK, N. Y., A CORPORATION OF DELAWARE

ECONOMIZER

Application filed October 1, 1927. Serial No. 223,301.

This invention relates to apparatus such as economizers, reheaters, superheaters, and the like, and one of its primary objects is to provide a simple, compact and efficient apparatus of this character.

Another object of the invention is to provide a device of this character in which corrosion of certain of the parts is effectively prevented.

10 A more specific object of the invention is the provision of novel supporting means for the tubes.

How the foregoing, together with such other objects and advantages as may herein-
15 after appear, or are incident to my invention, are realized, is illustrated in preferred form in the accompanying drawings, wherein—

Fig. 1 is a front elevation of an economizer embodying my invention with a portion thereof appearing in section.

Fig. 2 is an enlarged fragmentary longitudinal section through a portion of the economizer, the section being taken on the line 2—2 of Fig. 3, and

25 Fig. 3 is a cross section of Fig. 2 taken on the line 3-3 of Fig. 2.

Referring to the drawings, the economizer comprises, in general, a casing A having an inlet 4 for a heating medium, such as flue gas, 30 and an outlet 5 for said medium; a plurality of rows of tubes B, the tubes in this instance being horizontally disposed and connected at their ends for back and forth traverse there-through of water or other medium to be heated, and supports C, C for the tubes of the 35 rows of tubes.

The tubes of one row are offset with respect to the tubes of the adjacent row as shown in Fig. 3, and they are provided with longitudinally extending fins 6, preferably welded thereto, which fins cooperate with the tubes to provide a multiplicity of passes or divisions through which the gases pass, as will be clear from inspection of Fig. 3. The fins 6 transmit heat by conduction to the tubes B. It will be understood that the gases are caused to traverse the passages at fairly high velocity and that, in traversing the passages, the gases are alternately deflected from tube to tube, producing a thorough scouring

or sweeping of metallic surfaces which, in addition to obtaining effective heat transmission, minimizes the incrustation which takes place on the exterior of the heating surface. Efficiency is further increased by virtue of the fact that the water also traverses the tubes very rapidly, for the reason that it is possible to employ small tubes. This rapid flow in accordance with well known principles, increases efficiency and minimizes the formation of deposits or internal incrustations. Thus, the device can be operated for long periods without cleaning.

Referring now to the manner of connecting the tubes, it will be seen that the tubes of the lowermost row of tubes are connected into an intake header 7 and the water traverses the length of these tubes to the junction blocks 8, which may be of any one of a number of different kinds available for this purpose, and which connect the discharge ends of the tubes of the first row with the intake ends of the tubes of the next row. The water then traverses this second row of tubes to similar junction blocks or boxes 8 at the opposite ends which connect the discharge ends of the tubes of the second row with the intake ends of the tubes of the next row from which the water traverses this next row and so on. Ultimately, the water enters the outlet header 9 into which the tubes of the uppermost row connect. The junction blocks 8 are provided with readily detachable plugs 10 located in line with the tubes whereby access may be had to the tubes for cleaning and replacement purposes.

The supports C, C for the tubes of the rows of tubes B are located adjacent the ends of the tubes and are preferably spaced somewhat from the junction blocks 8. These supports constitute what may be termed "tube sheets." For convenience of manufacture and assembly, I have constructed each support of a plurality of castings adapted to be superimposed to constitute one large support or tube sheet. The lowermost and uppermost of these castings are preferably of like construction and the intermediate units are also of like construction which cheapens the cost of manufacture. The supporting mem- 90 95 100

bers are stiffened by means of the marginal flanges 11 and ribs 12. In addition to their stiffening feature, the ribs and flanges provide pockets, in this instance of diamond shape, for receiving filling material 13, such as refractory material, which acts as a seal to prevent gases from leaking past the supports C, C, into the end chambers 14, 14, provided between the supports and the end walls 15 5 of the casing A. Thus, it will be seen that the supports together with the filling material not only serve to support the tubes, but, in addition, serve as baffles or partitions providing chambers in the casing sealed 10 against the entrance of gases thereto. The tubes B project through these partitions and the junction blocks 8 above referred to are located in the chambers thus provided.

From the foregoing it will be seen that 20 gases are prevented from coming in contact with the headers which is important for the reason that should a tube leak at the junction block and the water from the leak come in contact with the flue gases containing a higher 25 percentage of sulphur dioxide, and acid would be formed and the tube would corrode very rapidly.

It is pointed out that by having the junction boxes spaced somewhat from the supports, I am enabled to incline the tubes if desired without interference with the supports. Space is thus also provided for moving the boxes toward the supports to facilitate 30 35 repairs.

In connection with the supports C, C, it is to be observed that the openings 16, see Figs. 2 and 3, in which a tube is omitted to clearly show the openings, correspond in contour to the cross section of the tubes with their fins, 40 by virtue of which I am enabled to readily remove the tubes from the end when replacement is necessary. A convenient method of applying the filling material 13 is to employ a form having holes corresponding in shape 45 and spacing to the holes in the supports.

In the particular embodiment shown, the water enters the economizer at the bottom and the gas at the top, this for counterflow purposes.

50 I claim:—

1. An economizer including a casing having a gas inlet and a gas outlet, a plurality of rows of tubes in said casing connected for back and forth traverse therethrough, and 55 means for supporting the tubes of said rows comprising flanged and ribbed tube sheets located adjacent the ends of the tubes, together with filling material in the pockets provided by the flanges and ribs of the tube sheets.

2. An economizer including a casing having a gas inlet and a gas outlet, a plurality of rows of tubes in said casing connected for back and forth traverse therethrough, and 60 65 means for supporting the tubes of said rows

comprising flanged and ribbed tube sheets located adjacent the ends of the tubes, together with filling material in the pockets provided by the flanges and ribs of the tube sheets, said tubes being provided with longitudinal fins, and said tube sheets having holes corresponding in contour to the cross section of the finned tubes.

3. An economizer including a casing having a gas inlet and a gas outlet, a plurality of rows of tubes in said casing connected for back and forth traverse therethrough, and means for supporting the tubes of said rows comprising tube sheets having means adapted to receive filling material.

In testimony whereof I have hereunto signed my name.

OTTO DE LORENZI.
